CUTTING MACHINE

Ewald Schutz, Lancaster, Pa., assignor to De Walt Products Corporation, Lancaster, Pa., a corporation of Pennsylvania

Application August 11, 1942, Serial No. 454,364

6 Claims. (Cl. 29—69)

This invention relates to cutting machines, and it is particularly applicable to machines for cutting pieces from stock that is in the form of rods, tubes, etc.

General objects of the invention are to provide a cutting machine having compactness, having high operating speed, having a high degree of safety, and having a high degree of operating ease and convenience.

Various additional and specific objects of the invention will be apparent to those skilled in the art from the following disclosure of forms of the invention which are at present preferred by me.

Fig. 1 of the drawings is a perspective view of the machine with the cover open and with part of the cover broken away.

Fig. 2 is a side elevation with parts broken away, looking from the right-hand side of the machine.

Fig. 3 is a top plan view of the machine with the cover closed.

Fig. 4 is an elevation of the upper portion of the machine, looking from the right-hand side of the machine, with the cover closed.

Fig. 5 shows a modification. The view is an elevation looking from the right-hand side of the machine, with the cover open and part of it broken away.

Reference will first be had to Figs. 1, 2, 3, and 4. The dangerous parts of the machine are substantially completely enclosed by an enclosure which includes a housing 1 and a hollow cover 2 that is hinged to the housing. A shaft 4 traverses the housing 1 and swingably supports a frame 5 (Fig. 2) which is adapted to swing back and forth. The upper portion of the frame 5 projects above the top of the housing 1 and has journaled therein a cutter shaft 6 on which is mounted a cutting disc 7. The disc 7 may be a suitable saw, or it may be an abrasive disc such as, for example, a molded phenolic disc having abrasive incorporated therein. Mounted on the lower portion of frame 5 is an electric motor 8 which, through a plurality of V-belts 9, is adapted to drive cutter shaft 6 and thereby rotate the cutting disc 7.

At the top of the housing 1 there is a table 12 on which is mounted a stationary V-support 14 and a vise designated as a whole as 15. Projecting laterally from the vise 15 is a rod 16 adapted to be adjusted in position and be clamped in any adjusted position by a clamp bolt 17. Rod 16 carries a block 18 which is adapted to be adjusted lengthwise and rotatably of rod 16 and be held in any adjusted position by thumb screw 19. Projecting from block 18, perpendicularly of rod 16, 55

is a second rod 20 which can be adjusted forwardly and backwardly of the machine and be held in adjusted position by thumb screw 21 which engages a flat on rod 20. The free end of rod 20 is provided with a screw 22 on the end of which is mounted a stop 22'. The stop 22' can be adjusted laterally of the machine by turning screw 22, and can be locked in place by winged lock-nut 23. In operation stock 25 in the form of a tube, rod or the like, is supported at one point by V-block 14 and clamped at another point by vise 15. By suitable adjustment of rod 16, block 18, rod 20, and stop 22', the stop 22' may be aligned with the end of the rod-like stock 25 from which pieces are to be cut. Thus stop 22' is an adjustable one against which the end of the stock 25 can be pushed; and it fixes the length of successive pieces which it may be desired to cut off.

Vise 15 includes fixed lower jaws 30 and 31 which are aligned, and which are separated by a slot 32 (Fig. 1) which runs forwardly and backwardly of the machine. The vise also includes a movable upper member 34 having aligned jaws 35 and 36 which are separated by slot 37 that corresponds to and is directly over the slot 32. The upper vise member 34 is mounted on a vertically reciprocatable rod 40 which is connected by transverse pin 41 with the upper end of a tension link designated as a whole by 42. The lower end of the tension link 42 is connected by a transverse pin 44 with a treadle 45. A tension spring 46 (Fig. 2) biases the treadle in upper (non-operated) position. A bolt 47 (Fig. 1) may have a nose that enters a longitudinal groove (not shown) in rod 40, to prevent any rotation of the rod as it is reciprocated.

In operation the cover 2 of the housing is closed, as shown in Figs. 3 and 4. This cover is provided with aligned openings at 2' and 3' (Figs. 3 and 4) so that the rod-like stock 25 can be inserted from the left, passing through the openings at 2' and 3' lying between the jaws of vise 15 and being positioned adjacent to the periphery of cutting disc 7. At the left side of the machine the stock 25 merely rests in V support 14. Upon depressing the treadle 45, the upper vise member 34 is pulled downwardly, causing the upper jaws 35 and 36 of the vise to clamp the piece against the lower jaws 30 and 31, respectively.

Pivoted to the housing at 48 (Fig. 1) is an operating link 49. Clamped to link 49 by bolt 50 is a hand lever 51; and interfitting serrations at 52 (Fig. 1) prevent any angular slippage between link 49 and hand lever 51. Nevertheless, the angle between hand lever 51 and link 49 can be ad-

justed by loosening bolt 50. Link 49 is pivotally connected to a pair of links 55, 55 (see Fig. 3) which in turn are pivotally attached at 56 to the top of the swinging frame 5. When hand lever 51 is depressed, the swinging frame 5 is swung forwardly, bringing the cutting disc 7 into cutting relationship with the stock 25 held in vise 15 and thereby cutting off the desired piece from the stock. As the cutting disc 70 moves forwardly, it passes into slots 31 and 32 between the respective pairs of upper and lower jaws of the vise. When the lever 51 is released, the frame 5 swings back to its rearward position due to the unbalanced weight applied to the frame 5 by motor 8. For convenience of illustration, the forward position of frame 5 and associated parts is shown in full lines in Fig. 2, and the rear position of the frame 5 and the cutter 7 is shown in dot-dash lines.

The housing may be ventilated by various sets of louvers such as the set shown at 60 in Fig. 1. An adjustable stop, preferably rubber tipped, is provided at 62 (Fig. 2) to limit the backward movement of swinging frame 5. A second adjustable stop, also preferably rubber tipped, is provided at 64 to limit the forward movement of swinging frame 5. At the front of the housing a hand wheel 66 may be provided to adjust stop 64. Included in the treadle operated tension link 42 there is preferably a turn buckle element such as 86 to adjust the length of link 42 to thereby adapt the vise 15 for handling stock of different diameters. The electric motor 8 which drives the cutting disc may be controlled by start and stop push buttons 67 and 68 respectively. To aid in unscrewing nut 69 when it is desired to replace cutter 7 means may be provided to temporarily lock the cutter shaft 6 against rotation. In Fig. 1 there is shown a plunger 70 which is biased upwardly by a spring (not shown). This plunger is adapted to be temporarily depressed by hand, its lower end engaging a flat on, or a hollow in, shaft 6 to hold the shaft against rotation when a wrench is applied to nut 69.

In operating the form of invention shown in Figs. 1 through 4, the stock 25 is advanced by hand after each piece is cut off. After the stock has been advanced, treadle 45 is operated to clamp it in the vise 15, and then the hand lever 51 is operated to swing the cutting disc 7 forward to cut off the piece. In the modification shown in Fig. 5 the stock is also advanced by hand, but the operation of both the vise and the cutting disc are under the control of a single hand lever. In Fig. 5 the hand lever 51 operates through links 49 and 55 to advance the swinging frame in the same manner as in Figs. 1 through 4. For the sake of illustration, hand lever 51 is shown in Fig. 5 as having been adjusted, through the loosening of nut 59, to a different angular relationship with respect to link 49.

At 70 there is an air valve assembly having a plunger 71 that is biased outwardly and is adapted to be pressed inwardly by lever 72. The valve is of known type and its construction is such that with the plunger 71 in outward position, air line 74 is vented. However, with the plunger 71 in depressed position, the venting of line 74 is closed and air pressure is delivered to line 74 from air supply line 75. Lever 72 is biased in non-operated position by spring 76, the tension of which is adjustable by turn buckle 77. A second spring 78, which is stronger than spring 76, is adjustably connected by turn buckle 79 with the pivot pin 56 of the swinging frame 5 (see Fig. 2). At 15a

the machine is provided with a vise having fixed jaws at 80 and movable jaws at 81. These jaws are slotted after the fashion of the jaws shown in Fig. 1 to permit the cutter 7 to advance. The movable jaw 81 is mounted for reciprocation forwardly and backwardly of the machine and is biased into vise-open position by tension spring 82. A pneumatic cylinder assembly at 83 is connected to jaw 81 to advance the jaw into vise-closed position upon air pressure being delivered to the cylinder at 83.

Stock having been put in place in the vise 15a, hand lever 51 is operated. During the initial movement of hand lever 51 air valve lever 72 is operated causing air pressure to be delivered to line 74 and cylinder 83. This advances the movable jaws at 81 and clamps the stock in the vise 15a. The continued movement of hand lever 51 brings the cutting disc 7 into cutting relationship with the stock clamped in the vise, just as in the case of Figs. 1 through 4. Upon completion of the cut, hand lever 51 is merely released. The unbalanced weight applied by motor 8 (Fig. 2) returns the cutter to the position shown in Fig. 5; and spring 76 retracts lever 72, thereby permitting the closing of air valve 70 and the venting of air line 74. Thus the vise is restored to open position.

In compliance with the patent statutes, I have disclosed the best form in which I have contemplated applying my invention, but it will be realized that the disclosure is illustrative of the invention rather than limiting the scope of the same.

35 What I claim is:

1. A cutting machine comprising: an enclosing structure, a frame swingably mounted within the enclosing structure, a motor mounted on the frame within the enclosing structure, a rotary cutter mounted on the frame and enclosed by said structure, a driving connection from the motor to the cutter, the driving connection being within the enclosing structure, the enclosing structure having an opening through which an article can be fed adjacent to the periphery of the cutter, clamping means within the enclosing structure operable to clamp the article at a point adjacent to the cutter, control means outside of the enclosing structure, and means operably connecting the control means to said clamping means to effect clamping of the article and operably connecting the control means to said frame to swing the frame and thereby bring the cutter into cutting engagement with the clamped article.

55 2. A cutting machine as in claim 1, in which a single operating member outside of the enclosing structure constitutes the control means for controlling the clamping means and the swinging of the frame.

60 3. A cutting machine as in claim 1, in which the control means outside of the casing operates an air valve to pneumatically actuate the clamping means.

65 4. A cutting machine comprising: an enclosing structure, a frame swingably mounted within the enclosing structure, a motor mounted on the frame within the enclosing structure, a rotary cutter mounted on the frame and enclosed by said structure, a driving connection from the motor to the cutter, the driving connection being within the enclosing structure, the enclosing structure having aligned openings through which an article can be fed adjacent to the periphery of the cutter, an adjustable stop outside of the enclosing structure and positioned to be engaged by the

article passing through said openings, a vise within the enclosing structure operable to clamp the article at a point adjacent to the cutter, control means outside of the enclosing structure, and means operably connecting the control means to said vise to effect clamping of the article and operably connecting the control means to said frame to swing the frame and thereby bring the cutter into cutting engagement with the clamped article.

5. A cutting machine comprising: a housing, a frame swingably mounted within the housing and projecting above the top of the housing, a motor mounted on the frame within the housing, a rotary cutter mounted on the frame and projecting above the top of the housing, driving connection from the motor to the cutter, a cover for closing the housing and enclosing the cutter, the cover having an opening through which an article can be fed adjacent to the cutter, a table beneath the cover, a vise on the table to clamp an article inserted through said opening, control means outside of the housing, and operating connections

from the control means to said vise to actuate it and to said frame to swing the same and thereby bring the cutter into cutting engagement with an article held in said vise; said control means being a single member controlling both the actuation of the vise and the swinging of the frame.

6. A cutting machine comprising: a housing, a frame swingably mounted within the housing and projecting above the top of the housing, a motor mounted on the frame within the housing, a rotary cutter mounted on the frame and projecting above the top of the housing, driving connection from the motor to the cutter, a cover for closing the housing and enclosing the cutter, the cover having aligned openings through which an article can be fed adjacent to the cutter, clamping means within the cover to clamp the article, an operating member outside of the housing, and operating connections from said member to swing said frame and thereby bring the cutter into cutting engagement with the clamped article.

EWALD SCHUTZ.
